ARMOR PLATE CONSTRUCTION

Maurice Partiot, Noroton, Conn., assignor to The Nitrally Corporation, a corporation of Delaware

Application February 5, 1943, Serial No. 474,815

3 Claims. (Cl. 109—85)

This invention relates to armor plate and particularly to armor plate of the laminated type, possessing high resistance to penetration and capable of deflecting projectiles which pierce the plate.

In applicant's copending application Serial No. 453,913 a novel type of laminated armor plate is described in which layers or sheets of hardened material are arranged to provide areas that are spaced apart to permit limited relative movement of the sheets in a direction normal to the outer surface of the plate. The laminae in the sheet are secured to each other in such a way that localized zones of weakness are largely, if not entirely, eliminated and the overall resiliency of the armor plate is improved.

In accordance with the present invention, armor plates of this character are further provided with means which serve to deflect a projectile engaging or penetrating the plate. The deflecting means are located beneath the outer surface of the plate and are inclined with respect thereto whereby a projectile penetrating the outer surface will be deflected if it should pass on into the plate. The deflecting means further serve to cause the outer surface of the plate to be shifted transversely with respect to an inner surface or lower laminae of the plate on compression of the plate under impact, whereby further deflection of the projectile is effected. Moreover, the yielding characteristics of the plate in directions both normal to and parallel to the outer surface thereof aids in preventing penetration of the plate by projectiles.

One of the objects of the present invention is to provide a novel type of laminated armor plate which possesses high resistance to penetration.

Another object of the invention is to provide armor plate with means embodied therein which serve to deflect projectiles engaging or penetrating the plate.

A further object of the invention is to provide armor plate formed of spaced sheets of material capable of limited relative movement in directions both normal to and parallel to the outer surface of the plate.

A particular object of the present invention is to provide a novel type of armor plate embodying spaced sheets of material having members located therebetween and inclined with respect to the sheets to deflect a projectile and to cause an outer sheet to move in a transverse direction with respect to an inner sheet or surface on compression of the plate under impact.

These and other objects and features of the

invention will appear from the following description thereof in which reference is made to preferred embodiments of the invention.

In the drawing:

5. Fig. 1 is a transverse sectional view through a laminated armor plate embodying the present invention;

Fig. 2 is a view partly in elevation and partly in section showing a portion of the construction 10 illustrated in Fig. 1;

Figs. 3, 4 and 5 are diagrammatic illustrations indicating the manner of operation of the plate of Fig. 1 upon impact of a projectile, and

Fig. 6 is a diagrammatic sectional view through 15 an assembly of armor plates embodying the present invention.

The construction shown in Fig. 1 embodies an outer sheet of material 2 and an inner sheet 4, which may be a surface of an object to be protected but preferably is a sheet of material similar to the sheet 2. These sheets are spaced apart and preferably are arranged in generally parallel relation.

Between the sheets 2 and 4 are a plurality of 25 deflecting members 6 which are in the form of strips extending across the plate from one edge of the plate to the other in substantially parallel relation. The strips preferably are formed in two separate pieces 8 and 10, having inclined and overlapping central portions 12 and 14 respectively. The piece 8 of each deflecting member has an edge portion 16 which extends parallel to the outer sheet 2 and is welded to the inner surface thereof at 18. The piece 10 of each deflecting member is similarly formed with an edge portion 20 welded at 22 to the inner face of the inner sheet 4. The overlapping central portions 12 and 14 of the deflecting members 6 are similarly inclined with respect to the sheets 2 and 4 and are 30 preferably parallel and in contact with each other but are capable of relative movement on compression of the plate under impact of a projectile. The armor plate may thus be formed in two separate parts, one of which is composed of the sheet 2 with the pieces 8 welded thereto and the other composed of the sheet 4 having pieces 10 welded thereto. These two parts can then be assembled 35 as shown and can be bolted or otherwise secured together to form the completed armor plate with the deflecting members 6.

The angle at which the central portions of the deflecting members 6 are inclined to the adjacent sheets and the spacing of the deflecting members from one another is preferably such that these members project over each other as shown.

When the deflecting members are so arranged, a projectile, in order to pass through the armor plate in a direction normal to the sheet 2 and in the zone shown by the line A—A in Fig. 1, would have to pass through the sheet 2, then through the reinforcing edge portion 16 of the outer piece 8 of one deflecting member, then through the overlapping inclined portions 12 and 14 of the pieces forming an adjacent deflecting member, thence through the reinforcing edge portion 20 of the piece 10 of next adjacent deflecting member and finally passing out through the inner sheet 4. It will thus be seen that the armor plate presents six successive layers or sheets of material which would have to be penetrated by any projectile passing in a normal direction through such portions of the plate. In case the projectile happens to pass through the plate in an intermediate zone, it will still have to penetrate five layers or sheets of the protection material.

However, with the armor plate constructed as shown, a projectile will not pass directly through the armor plate in a straight line as described, since the nose of the projectile on engaging the inclined surface of the deflecting member will be turned or deflected laterally. On further penetration through the plate, after such deflection, the projectile can only engage the reinforcing edge portion 20 of the deflecting member or the inner sheet 4 at such an angle thereto that its chances of penetrating the inner sheet and passing completely through the armor plate are greatly reduced. Moreover, the central portions 12 and 14 of the deflecting members are not rigidly secured together but are free to move and bend under the impact of a projectile. Therefore, a large part of the energy of the projectile will be expended in bending or distorting the deflecting members whereby the inertia of the projectile is reduced and the possibility of complete penetration of the armor plate is further diminished.

Furthermore, as shown in Fig. 1, the deflecting members are all inclined in the same direction so that compression of the plate under impact tends to cause the inclined portions of the deflecting members to move about their points of contact with the inner and outer sheets as pivots. The outer sheet will therefore tend to be displaced laterally with respect to the inner sheet, moving to the left, as seen in Fig. 1. Thus, transverse movement of the outer sheet under impact further serves to deflect the projectile on engagement with or penetration thereof into the armor plate.

The action of the armor plate will differ under different types of impact and when struck by different types of projectiles. Typical actions are shown in Figs. 3, 4 and 5.

As shown in Fig. 3, a projectile 24 striking the armor plate in a direction normal to the outer surface thereof may penetrate the outer sheet 2 so as to engage the deflecting member 6. This member, being inclined, tends to deflect the projectile to the right as seen in Fig. 3. Moreover, the nose of the projectile is so inclined to the deflecting member that it presents a relatively flat or curved surface thereto and tends to crush or deform the member instead of penetrating therethrough. Furthermore, the member 6 embodies two pieces of material having relatively movable portions 12 and 14 so that these parts bend or are distorted by the projectile until they

engage edge portion 20 of the next adjacent deflecting member or the inner sheet 4 of the armor plate, as shown in dotted lines in Fig. 3. The energy expended in thus deforming the portions 12 and 14 of the deflecting member and the frictional resistance which the engaging surfaces of the portions present to relative movement as they are deformed, serve to decrease the inertia of the projectile and finally present it in an inclined or broadside position to the multiple layers of steel which back up and reinforce each other to prevent complete penetration of the projectile through the armor plate.

As shown in Fig. 4, if a projectile approaching the plate in a direction normal to the outer sheet 2 is partially spent or if the outer sheet 2 is of such strength that the deflecting members yield somewhat before the nose of the projectile has penetrated very far through the sheet, the outer sheet 2 will be forced inward compressing the armor plate. As a result of this compression, the outer sheet will be shifted to the left as seen in Fig. 4, deflecting the nose of the projectile to the left before it engages the deflecting member 26. The deflecting members 26 shown in Fig. 4 are formed of a single integral element but it will be apparent that they may be of the two piece construction shown in Fig. 1, and in fact, such two piece formation is preferred.

When so deflected by movement of the outer sheet 2 of the armor plate, the projectile will be presented in a substantially normal position to the deflecting member but on penetration thereof, it will approach the end portion 28 of an adjacent deflecting member and the rear sheet 4 of the armor plate at such an angle that final deflection thereof is assured and complete penetration of the armor plate prevented.

If, as shown in Fig. 5, the projectile penetrates the outer sheet 2 (and edge portion 16 of a deflecting member) before much compression of the armor plate takes place, the nose of the projectile will engage the inclined portion of the next adjacent deflecting member at such an angle that it will be diverted from its normal path of travel through the plate. Furthermore, the impact of the projectile on the inclined portions of the deflecting member will instantly and forcibly shift the outer sheet 2 to the left, as seen in Fig. 5, and thus will throw the tail of the projectile sideways, further deflecting the projectile as shown in dotted lines and decreasing its chances of complete penetration.

It will be noted that the arrangement of the deflecting members shown in the figures of the drawing is such that a projectile that is not substantially spent and forcibly penetrates the outer sheet of the armor plate, as indicated by Figs. 3 and 5, will be deflected to the right if it should penetrate through the rear sheet 4 and emerge from the armor plate. It will be apparent, however, that the deflection of the projectile would be toward the left, if the deflecting members were inclined in the opposite direction. It is, therefore, possible to arrange a number of armor plates so as to deflect projectiles in opposite directions from a particular area to afford the greatest protection therefor. Thus, as shown in Fig. 6, the plate 30 is constructed and positioned to deflect bullets to the left, while plate 32 will deflect bullets to the right, leaving a more thoroughly protected area 34 which may be the cockpit of a plane, a magazine in a boat, the breach portion of a gun, or any other vital parts such as portions of a tank, reconnaissance car, or the like. The

joint between these plates may be covered by a specially armored retaining member 36, which serves to hold the plates 30 and 32 in place.

In constructing the armor plate, the sheets 2 and 4 and the pieces from which the deflecting members 6 are formed are preferably thin sheets of steel having high resistance to penetration by armor piercing bullets. Each of the sheets and pieces may be individually nitrided or otherwise case hardened either before or after the elements are assembled into the finished armor plate. If they are hardened prior to assembly in juxtaposed interlocking relation, the adjacent surfaces of the pieces 12 and 14 of which the deflecting members are formed will each be more evenly hardened so that the total thickness of the hardened layers will be increased and the resistance to penetration improved as compared with hardening of the armor plate structure after the plates with their attached deflecting members have been assembled in such juxtaposed interlocking relation.

In assembling the elements into a finished armor plate, the reinforcing edge portions 16 of the pieces 8 of the deflecting members are welded to the outer sheet 2, progressing from right to left so that the point to be welded is readily accessible. Thereafter, the edge portions 20 of the pieces 10 of the deflecting members are welded in a similar manner to the inner sheet 4 progressing from left to right thus forming two independent structures. The terminal piece of each deflecting member is provided with a reinforcing piece 38 which is welded thereto to give it strength and penetration resistance comparable with that of the overlapping portions 12 and 14 of the intermediate deflecting members. The end portion of each plate is also provided with a reinforcing plate 40 as shown in Figs. 1 and 2. The structures thus formed are then assembled with the portions 14 of the pieces secured to the inner plate 4 overlapping the portions 12 of the pieces secured to the outer plate 2. The structures are held in assembled relation by any suitable means but are preferably secured together by bolts 42 which pass through bolt holes 44 in the plates 2 and 4 which are sufficiently larger than in the bolts to permit the desired relative movement of the plates with respect to each other.

The welding operations may, of course, be carried out simultaneously at various points at the same time by the use of welding equipment having multiple electrodes and by suitably clamping the elements together in a jig or other suitable fixture. In any case, when welding the elements together, it is desirable to locate the welded spots in staggered or "index spaced relation," that is, in such a manner that no two or more welds are in alignment in a direction normal to the surface of the assembled plate. In this way, any areas which are softened by the welding operation are so displaced with respect to each other that there are no overlapping or localized areas of weakness which might permit the penetration of a projectile through the armor plate.

While the invention has been shown in the drawing as composed of a single armor plate, including only two parallel sheets with deflecting members between the same, it will be evident that any number of armor plates or plates embodying any number of alternate layers of sheets and deflecting members may be produced and assembled as desired to provide the necessary protection to any given area. It will also be apparent that the form, shape and arrange-

ment of the deflecting members and sheets, and their positions with respect to each other, may be varied considerably without departing from the spirit of the invention. In view thereof, it should be understood that the preferred form of the invention shown in the drawing and described above is intended for illustrative purposes only and is not intended to limit the scope of the claims.

10 I claim:

1. A composite armor plate comprising a pair of sheets of metal arranged in superposed spaced relation and having a series of deflecting members located therebetween, said members being formed of sheet metal and arranged in pairs with a portion of each member arranged in overlapping parallel relation to a like portion of the other member of the pair and extending obliquely outwardly toward the opposing sheet, one of said members having a marginal portion thereof bent to conform to the surface of one of said sheets and secured thereto, the other member of each pair having a like marginal portion bent to conform to the surface of the opposite sheet and being secured thereto, and said members having their opposite ends free, said overlapping parallelly arranged portions of said members also being of such length and inclination as to overlie, on the one side, the bent marginal portion of one member of the next adjacent pair of deflecting members and to underlie, on the other side, the bent marginal portion of one member of the pair of deflecting members next adjacent on the opposite side of the first mentioned pair of deflecting members.

2. A composite armor plate comprising a pair of sheets of metal arranged in superposed spaced relation and having a series of deflecting members located therebetween, said members being formed of sheet metal and arranged in pairs with a portion of each member arranged in overlapping parallel relation to a like portion of the other member of the pair and extending obliquely outwardly toward the opposing sheet, one of said members having a marginal portion thereof bent to conform to the surface of one of said sheets and welded thereto, the other member of each pair having a like marginal portion bent to conform to the surface of the opposite sheet and being welded thereto, and said members having their opposite ends free, said overlapping parallelly arranged portions of said members also being of such length and inclination as to overlie, on the one side, the bent marginal portion of one member of the next adjacent pair of deflecting members and to underlie, on the other side, the bent marginal portion of one member of the pair of deflecting members next adjacent on the opposite side of the first mentioned pair of deflecting members.

3. A composite armor plate comprising a pair of sheets of metal arranged in superposed spaced relation and having a series of deflecting members located therebetween, said members being formed of sheet metal and arranged in pairs with a portion of each member arranged in overlapping parallel relation to a like portion of the other member of the pair and extending obliquely outwardly toward the opposing sheet, one of said members having a marginal portion thereof bent to conform to the surface of one of said sheets and welded thereto, the other member of each pair having a like marginal portion bent to conform to the surface of the opposite sheet and being welded thereto, and said members having

their opposite ends free, said overlapping parallelly arranged portions of said members also being of such length and inclination as to overlie, on the one side, the bent marginal portion of one member of the next adjacent pair of deflecting members and to underlie, on the other side, the bent marginal portion of one member

of the pair of deflecting members next adjacent on the opposite side of the first mentioned pair of deflecting members, and the points at which said members are welded to said sheets being arranged so that no two weld spots are in alignment in a direction normal to the plate.

MAURICE PARTIOT.
